BUILDING

Austin T. Levy, Harrisville, R. I.

Application August 27, 1937, Serial No. 161,268

23 Claims.

(Cl. 72—1)

My invention relates to buildings of the prefabricated type such as described in my applications, Serial Nos. 46,156, filed October 22, 1935; 54,429, filed December 14, 1935, and 76,950, filed

5 April 29, 1936.

My invention relates to a partition structure for a building of this type and is a continuation in part of my copending application Serial No. 89,960, filed July 10, 1936.

10 One of the objects which I have in view is the provision of an improved partition made up of prefabricated parts, which combines the advantages of simplicity, strength, cheapness, effective thermal and sound insulation, and rapidity of erection by relatively unskilled labor.

Another object of my invention is to provide a partition structure of the type in which the partition includes studs and wall panels extending from floor to ceiling, in which the studs and 20 panels can be quickly installed and coatings of plaster readily applied to and securely anchored over the studs and panels.

Another object is to furnish an improved arrangement of studs and panels in a partition structure and to provide an improved partition panel and improved means for supporting the studs and panels relative to each other and to the floor and ceiling.

These and other objects of my invention will, 30 however, appear more clearly hereafter, or be apparent to those skilled in the art.

In the accompanying drawings, in which I have shown several embodiments of my improved partition structure,—

35 Figure 1 is an elevation partly broken away of a portion of a small building such as a dwelling house constructed in accordance with my invention;

Fig. 2 is a perspective view partly broken away, 40 and partly in section, with certain parts omitted, showing a portion of an outer wall and portions of certain partitions;

Fig. 3 is an enlarged horizontal section through a portion of one of the partitions;

45 Fig. 4 is an elevation partly in section and partly broken away showing the lower portion of a partition structure such as shown in Fig. 3;

Fig. 5 is a view generally similar to Fig. 4, 50 illustrating a modified construction of the lower portion of the partition;

Fig. 6 is a vertical transverse section taken on line 6—6 of Fig. 5;

55 Fig. 7 is a vertical transverse section through the upper part of a partition, illustrating a modi-

fied arrangement of the ceiling coating anchoring material;

Fig. 8 is a detail section taken at right angles to Fig. 7;

Fig. 9 is an elevation partly in section showing the lower portion of a partition used in a building having a concrete floor as distinguished from a wooden floor;

Fig. 10 is a perspective view showing a further modification of the lower part of the partition structure, this form also being used in connection with a concrete floor;

Fig. 11 is a detail face view of one of the partition panels;

Fig. 12 is a perspective view of a modified construction, viewed from inside the house, showing a partition and its mounting on a floor beam, together with the ceiling supports above the partition, and

Fig. 13 is a vertical sectional detail through a partition of this modified construction with the ceiling and floor in place.

The building shown in Figs. 1 to 4 is of the structure described in my application, Serial No. 76,950, above mentioned, and comprises a foundation A, an outer wall B including studs C and wall panels D, and a hip roof E. As described in said application and in my other previous applications, each of the panels D preferably comprises a board 10, of compressed wood fiber or like thermal insulating material, of story height, having applied to each face thereof a series of longitudinal reenforcing and locking rods 11. These rods serve to space from the board sheets 12 of coating anchoring material or metal lath, 30 which may, as herein shown, be formed of woven wire. If desired, expanded metal may be used or some other form of reticulated material.

The sheets 12 and the rods 11 are fastened to the board by means such as wire loops 13 arranged at suitable intervals in the length of the rods and passing through suitable perforations in the board. The arrangement is such that the rods 11, lying against opposite faces of the board and firmly secured thereto, considerably increase 45 the resistance of the panel to buckling strain and also space the anchoring sheets from the board face. After the fastening wires have been placed in position, the ends of the wires are twisted together so as to tightly clamp the rods 50 against the board and the anchoring sheets against the rods. The ends of the rods, located adjacent the upper and lower edges of the panel, project slightly beyond the edges of the board 55 so as to act as means for locking the wall panels

to the lower plate members and to the upper plate members. The lateral edge portions of adjacent sheets 12 are adapted to overlap the stud members positioned adjacent the lateral edges of the board and to overlap each other. This structure is employed at the inner face of the outer wall as well as at the outer face.

The foundation A is preferably made of concrete, and to the upper face of the wall the 10 metallic lower plate member 14 is applied. At an end (or side) of the building, this plate member comprises a wide plate portion or flange 15 suitably secured to the foundation as by bolting it thereto, and it also comprises an upstanding portion 16 having an inwardly directed flange 17. A wooden board floor 18 rests on the floor beams 19 and on the flange 17. The studs of the outer wall are fastened to the upstanding portion 16 in the manner described in my application Serial No. 76,950. At a side (or end) of the building, a generally similar arrangement of upstanding plate or sill portion to which the studs are fastened is used, as described in that application.

The plate portion or flange 15 is provided at intervals with suitable perforations 20 to receive the lower extended ends of the inner and outer rods 11 of the panels D. The rods may also extend into shallow sockets formed in the concrete in alignment with the perforations 20, as indicated by dotted lines in Fig. 2. The studs of the outer wall preferably comprise channel members placed back to back and suitably interconnected as by welding. These studs have their lower ends in engagement with the upper face of the member 15 and are secured to said member by suitable means such as angle plates 21. The channels of the studs receive and position the side edges of the panel boards and extend within the projecting lateral edges of the coating anchoring sheets.

The upper plate member 22 of the outer wall is preferably of ribbon like character, comprising a thin web or plate having perforations 23 for receiving the upper ends of the outer and inner locking rods 11. In a structure of this character the roof rafters and ceiling joists (not shown) are supported by wall studs located directly beneath the same, and therefore a ribbon-like upper plate member can be successfully employed. This plate member rests at intervals on plates or pads secured as by welding to the upper ends of the wall studs.

The wall panels and the wall studs are covered on the outside by a layer of cementitious material 24 such as stucco, and on the inside by a layer of cementitious material 25 such as plaster.

Where partitions are provided, they are usually placed in line with studs of the outer wall, in which case the stud C comprises, in addition to the usual channels 26, arranged back to back and welded together, an inwardly facing channel 27 directed at right angles to channels 26 and welded to them. The channel 27 is shorter than the channels 26, extending downwardly only as far as the upper surface of the floor. This channel 27 receives an edge of a partition panel 28. Usually the partition panels 28 are thinner than the panels D of the outer walls, but they are constructed in a similar manner, having reinforcing rods 11' and coating anchoring sheets 12' applied to opposite faces of the board and secured by fastener loops 13' in the manner previously described. Between the panels 28 of a partition, studs 29 having oppositely facing channels 30 are employed. These studs may be attached at their

lower ends to the boards of the wooden floor 18 by suitable means such as nails 31 passing through attaching plates or pads 32 welded to the lower ends of the studs. The lower ends of the rods enter sockets 33 formed in the floor in a suitable manner as by boring. The anchoring sheets 12' have extended side edges, as in the case of the outer wall panels, which edges overlap the studs 29 and overlap each other, as indicated at 34 in Fig. 3. It will also be understood that the sheets 12' carried by the board received in stud channel 27 extend over said channel at the sides thereof, the extended edges of said sheets being cut off or turned aside owing to the proximity of the outer wall panel receiving channels connected to 15 said channel 27.

On top of the stud having the channels 26, 27 is placed a T-shaped plate or pad 35 attached to the stud as by welding it thereto, said plate or pad supporting the outer wall plate member 22 previously described and also supporting the end of a partition plate member 36 secured to said plate or pad 35 as by welding it thereto. The partition plate member 36 is supported at intervals by and attached to plates or pads 37 welded to the upper ends of the partition studs 29. Where partitions intersect, studs 38 having four channels are employed. These studs have cross-shaped bottom plates 39 secured by suitable means such as nails 40 to the wooden floor. At the top of 30 the stud 38 a cross-shaped plate or pad 41 is provided for supporting and attaching the plate member sections appurtenant to the partitions. Each partition plate member is similar to the plate member 22 of the outer wall, but usually 35 somewhat narrower, and is provided with perforations 42 to receive the locking rods of the partition panels 28 and further provided adjacent opposite margins with longitudinally spaced small perforations 43 to receive fasteners 44 supporting the woven wire or other metal lath 45 of the ceiling. The fasteners are usually constituted by wire loops having portions passing through the perforations 43 and through interstices of the ceiling lath. Along its inner margin 45 the plate member 22 is provided with similar small perforations 46 by means of which the ceiling lath is attached to said plate member through the use of similar fasteners, as shown in Fig. 2.

The ceiling joists (not shown), when they cross the partitions, are only in those locations where studs are provided in the partition structure, said joists resting on the partition plate member at points directly over studs. As the 55 partition plate member is relieved of ceiling joist load in the intervals between the studs, it can be of thin, ribbonlike character, which makes it inexpensive, light in weight and easy to handle, while at the same time it offers very effective resistance to lateral dislocation of the partition panels locked thereto by means of the locking rods.

It will be understood that the partition members having the structure above described can be 65 very readily installed in the building. After the partition stud members have been placed in the proper positions and attached at their lower ends to the floor, the panels are inserted from above into the channels so that the lower ends of the 70 rods enter their sockets in the floor. The lower edges of the panel boards rest on the floor. The plates or pads are then fastened to the tops of the studs as by welding, and the partition plate member connected as by welding to the stud 75.

pads. When the partition plate member is placed in position, its perforations 42 are placed in engagement with the upper projecting ends of the locking rods of the panels. After the partition plate members have been attached to the upper ends of the studs, the ceiling joists are placed in position over the studs. The plaster coatings applied over the partition panels and studs at opposite faces of the partition are indicated by dotted lines in Fig. 3. These coatings can be very readily applied and are effectively anchored by the sheets 12' which are held in spaced relation to the panel boards by the rods 11'. The ceiling plaster (not shown) is anchored by the 15 ceiling anchoring material 45 connected to the outer wall plate member, the partition plate members and the ceiling joists, the connection with the ceiling joists being, if desired, of the nature disclosed in my application Serial No. 20 76,950.

In the form shown in Figs. 5 and 6, the lower part of the partition is of a different structure, the partition panels and the partition studs being received in a shoe or sill constituted by an upwardly facing metal channel member 47 attached to and resting on the wooden floor 18. The partition studs 48 as before are constituted by channel members connected back to back, and their lower ends may be fastened as by welding in the 25 channel member 47. In this case, the lower ends of rods 11a are flush with the lower edge of the panel board 49 so as to rest, with said lower edge, on the bottom of the channel. The channel is of such width as to receive snugly the 30 board having the rods applied to its opposite faces. In this case the reticulated sheets 12a pass down over the outer side faces of the channel into proximity to the floor, as shown. In this construction, the channels of the studs and sill 35 or shoe effectively hold the panel against lateral or longitudinal displacement. It is preferable, however, to have the upper ends of the rods 11a interlock with a ribbonlike upper plate member in the manner previously described.

45 In the form shown in Figs. 7 and 8, the partition is shown at F and is used in connection with a modified arrangement of ceiling plaster anchoring material. In this case the metal lath 50 for the ceiling is attached to small channels 51 having upper and lower flanges, the upper flanges being attached as by welding to the lower surface of the ribbonlike partition plate member 52. The channels 51 extend through notches 53 cut in the upper ends of the panel boards, so 50 that said channels intersect the partition and have portions disposed at opposite sides thereof. The notches 53 can be formed very readily. The metal lath for the ceiling plaster is fastened at 55 intervals against the lower flanges of the channels by means such as wire fastener loops 54.

As disclosed in Fig. 7, the partition may extend in the same direction as a ceiling joist 55, in which case it may advantageously be located slightly to one side of the joist, as shown. Between the ceiling joists, boards 56 of suitable insulating material may be placed if desired. The channels 51 may advantageously be fastened to certain of the ceiling joists at points where they cross the same, as will be understood.

70 In the form shown in Fig. 9, a concrete floor is employed. In this case the partition stud 57, which is of the double channel type hereinbefore described, is connected by rivets 59a at its lower end to a floor beam 58 by means of angle plates 75 59 of which only one is shown and presenting

a stud receiving channel therebetween. The lower edges of the partition boards rest on the floor beams. Concrete is laid on these beams in any suitable manner, said concrete preferably having a suitable metallic reenforcement such as 5 the woven wire 60. The concrete comes to a level such as indicated by the dotted line in Fig. 9, and embeds the lower ends of the studs and partition panels, entering the interstices of the 10 wire sheet portions at the lower ends of the panels and thus very firmly anchoring the panels. The concrete floor may comprise a brush coat applied to the reenforcement 60, and a later-applied upper coat.

In this form, as in the forms previously described, the channel 27a forming part of the outer wall stud is shorter than the other channels of said stud. It extends downwardly only to the level of the upper faces of the floor beams.

In the modification shown in Fig. 10, also, a 20 concrete floor is employed. In this case, as in the form shown in Figs. 5 and 6, the partition panels and studs are received in a sill member or shoe constituted by an upwardly facing channel member. In the structure of Fig. 10, the channel 25 member 62 extends across and is supported by the floor beams, and the partition stud 61 enters at its lower end the channel of channel member 62, with its flanges lying against the inner faces of the side walls of the channel and riveted there- 30 to by rivets 62a passing through angle plates 63. These angle plates are also riveted to the upper surface of a floor beam 63a on which the channel member rests. In this form, the channel member 62 is narrower than the corresponding member 35 shown in Figs. 5 and 6, and does not receive the locking rods of the panels. In those locations where the locking rods are provided, the channel is cut away at the sides to provide horizontal lugs 64 lying in the plane of the bottom and 40 each provided with a perforation 65 to receive the lower end of a locking rod.

The concrete floor comprises a brush coat 66 applied to a metallic reenforcement 67 supported on the floor beams, and a subsequent thicker 45 upper coat 68. The plaster applied to opposite faces of the partition panels and studs is shown at 69.

In the form shown in Figures 12 and 13, a stud C of the outer wall, in addition to the previously 50 described oppositely facing channels 26, is provided with an inwardly directed single channel member 27 welded thereto at the back within the side margins thereof, similar to that previously described, and a partition panel 28 has its outer 55 edge disposed in this channel member 27 and between the same and the adjacent channel 30 of a double channeled partition stud member 29 as heretofore described. The channels 26 comprising stud C are suitably fixed to an angle sill 60 70 having one flange embedded in the foundation A, by means of an angle plate 71, while the partition stud 29 is suitably attached at its lower end as by angle plates 72 to the top of a floor beam 19. The channels comprising the studs 65 73 have bearing plates, or pads, 71a, welded to the ends thereof adjacent the plate members. Here also it will be noted that the upper ends of the partition panels 28 are suitably connected by their rods 11' in apertures 73 in bottom flanges 70 74 of plate members 75 which herein consist of two horizontally disposed channels welded back to back. Herein these members 75 also carry the upper channel joists 76 suitably interconnected with each other by a plate at 77. Further 75

these members 75 have applied at their outer ends angle plates 78 for connecting them to the members 79 comprising the plate members of the outer wall and formed generally similar to the partition plate members 75. Thus, it will be evident that the partition will be so securely positioned and connected to the outer frame structure as to cooperate effectively therewith in providing a support for the ceiling and roof structure.

As regards the ceiling structure, note that a ceiling 80 is provided (Fig. 13) which is suitably supported by the ceiling joists 76 heretofore described. As shown in Figure 13, the ceiling 80 includes metal lath 81 suitably attached to the joists 76 in any well known manner as by wiring or the like and adapted to carry a coating of plaster. Thus, when the walls and partitions and the ceiling are coated with their inner coat of plaster, a satisfactory interior finish for the walls and ceiling is obtained. Further, when the floor 82 is poured on the floor beams 19, the partitions and the outside walls are very firmly joined together, the lower ends of the studs and the partition panels being embedded in the concrete floor.

By my invention an improved partition is provided which is made of prefabricated parts that can be manufactured at low cost and quickly assembled with a minimum amount of labor. The structure is simple and of relatively light weight and yet strong and durable and provides not only for effective thermal and sound insulation but also for the ready application and firm anchoring of the coats of plaster or like material forming the inner finish. The number of separate parts is also reduced to a minimum. While the panels are of story height, they can be readily handled and assembled, and securely interlocked with the upper plate member. The panels are also effectively secured against dislocation at their lower parts. The plate member is also of simple form and light weight and readily handled and assembled. Preferably the distance between adjacent partition studs is of the order of four feet, and from this it will be seen that the number of parts in a partition of given length is quite small, yet the structure is exceptionally strong and rigid, due to the panel reinforcements and the provisions for positioning the panels at their side edges. The means for securing the studs in place are also simple and effective. It is also noted that the ceilings can be provided in a simple and expeditious manner. These and other advantages of my improved structure will be apparent to those skilled in the art.

While I have shown and described herein several embodiments which my invention may assume in practice, it will be understood that these are illustrative merely and that numerous other embodiments and many changes in details are within the scope of the invention as defined in the claims.

65 What I claim as new and desire to secure by Letters Patent is:

1. A partition structure for prefabricated buildings comprising a stud having oppositely disposed channels and a partition carrying channel at right angles to and fixed to said channels, wall and partition forming panel units seated in said channels and having reenforcing means thereon, and plate members connected to said stud and overlying said units and cooperating with said reenforcing means in positioning the panels.

2. A partition structure for prefabricated buildings comprising a stud having oppositely disposed channels and a channel at right angles to and fixed to said channels, wall panel units seated in said first named channels and having reenforcing means on the faces thereof, a partition panel seated in said second named channel and having reenforcing means on the faces thereof, and plate members resting on and connected to said stud and cooperating with said reenforcing means in positioning said panels.

3. A partition structure for prefabricated buildings comprising a stud having oppositely disposed channels and a channel at right angles to and fixed to said channels, wall panel units seated in said first named channels and having upwardly projecting reenforcing rods, a partition panel seated in said second named channel and having upwardly projecting reenforcing rods, a wall plate member supported on said stud and having means receiving the rods of said wall panel units, and a partition plate member supported on said stud and having means receiving the rods of said partition panel.

4. A partition structure for prefabricated buildings comprising a wall stud having oppositely disposed channels for receiving wall panels and a partition channel at right angles to said first named channels for receiving a partition panel, wall and partition panels seated in the channels and having reenforcing means applied to the faces thereof and projecting upwardly beyond the upper edges of the bodies of said panels, and plate members supported on said stud and overlying said panels and interlocked with the projecting reenforcing means thereof.

5. A partition structure for prefabricated buildings comprising a stud having oppositely disposed channels for receiving wall panels and a partition channel at right angles to said first named channels for receiving a partition panel, a pad on the upper end of said stud, wall panels seated in said first named channels and carrying anchoring sheets for a cementitious coating, a partition panel seated in said partition channel and carrying anchoring sheets for a cementitious coating, wall and partition plate members supported on said pad, and means associated with said plate members for preventing the lateral dislocation of said panels.

6. A partition structure for prefabricated buildings comprising a stud having oppositely disposed channels for receiving wall panels and a partition channel at right angles to said first named channels, panels seated in said channels and having reenforcing means projecting upwardly from the panel bodies, and ribbon-like plate members supported on said stud, one of said plate members being interlocked with the reenforcing means of the wall panels and the other plate member being interlocked with the reenforcing means of the partition panel.

7. In a building, a frame having studs arranged in angularly related series, the studs of one of said series being outer wall studs and those of another being partition studs, plate members associated with said studs, panels between said studs carrying coating anchoring material, a coating applied to said material, ceiling anchoring material attached to said plate members, and a ceiling coating applied to said last named material.

8. In a building, an outer wall including a frame having studs and an upper plate member, a partition including a frame having studs and

an upper plate member, panels between said studs forming parts of said wall and partition, and anchoring material for a ceiling coating attached to and supported by said wall and partition at the tops of said panels.

9. In a building, a wall stud having oppositely disposed channels for receiving wall panels and a partition channel at right angles to said first named channels, wall panels of story height in 10 said channels, partition studs having oppositely disposed channels, partition panels of story height interposed between adjacent partition channels and having coating anchoring material applied thereto extending over the studs, and 15 plate members extending over said wall and partition studs and interlocked with the panels.

10. In a building, a foundation, floor beams supported thereon, an outer wall stud supported on the foundation having oppositely disposed 20 wall panel receiving channels and a partition channel at right angles thereto, a floor supported on the floor beams, partition studs supported from said floor beams and having oppositely disposed channels, wall panels received in the oppositely 25 disposed channels of said first named stud, partition panels interposed between the partition studs and between one of said partition studs and said first named stud, means for connecting said partition panels to the floor, said wall and partition 30 panels having at their faces reenforcing means, and plate members connected to said studs and engaging the reenforcing means of the panels for positioning the panels.

11. In a building, a foundation, floor beams 35 supported thereon, a floor, an outer wall stud member supported on the foundation and having wall panel channels and a partition channel, a plurality of partition stud members supported by the floor and having oppositely disposed channels, a plurality of partition panels between the 40 partition stud members, a partition panel between one of the partition stud members and the outer wall stud, said outer wall stud having its partition channel of less length than the wall panel channels and engaging said partition panel above the 45 floor level, said partition panels being supported at their lower ends from the floor, an upper partition plate member interconnecting said partition studs, and means for positioning the upper 50 ends of the partition panels with respect to said plate member.

12. In a partition structure for buildings, the combination of a floor, partition studs fastened to and extending upwardly from said floor and 55 having oppositely disposed channels, partition panels received in said channels, means for interlocking said panels at their lower ends with the floor, and coating anchoring sheets applied to said panels and extending over the studs.

60 13. In a partition structure for buildings, the combination of a floor, a channeled member fixed to said floor, and a partition panel having a body whose lower edge is received in the channel of 65 said member and having at opposite faces of said body coating anchoring sheets extending over said channel.

14. In a partition structure for buildings, the combination of a floor, a channeled member fixed to said floor, a partition panel having a body 70 whose lower edge is received in the channel of said member, reenforcing rods applied at opposite faces of said panel, and coating anchoring sheets spaced from the body of said panel by said rods and extending over the outside of said channeled member.

15. In a partition structure for buildings, the combination of a floor, a channeled partition sill fixed to the floor, channeled partition studs received in said sill, and partition panels having edge portions received in the channel sill and in 5 the channels of the studs.

16. In a partition structure for buildings, a floor, a channeled partition sill or shoe resting on the floor, and a partition panel having reenforcing rods at the faces thereof received in said sill 10 and coating anchoring sheets applied to the re-enforcing rods and extending over the sides of the sill or shoe.

17. In a partition structure for buildings, a partition comprising panels, ceiling supporting 15 members extending through said panels, and anchoring material carried by said members and underlying the bottom faces thereof.

18. In a building, a partition structure comprising a panel cut away adjacent the upper edge 20 thereof, a supporting member extending through said cut away portion and having portions disposed at opposite sides of the partition, and ceiling anchoring material applied to said supporting member.

25 19. In a partition structure for prefabricated buildings, a partition support, a partition stud extending upwardly from said support, a stud connecting pad on said support beneath said stud and fixed thereto and to said support, partition 30 panels positioned by said stud and extending upright from said support, reenforcing means on opposite faces of said panels and having their lower ends laterally positioned by said support, coating anchoring means applied to the faces of said 35 panels and extending over said studs and spaced apart from said panels by said reenforcing means, and cementitious coatings on said anchoring means.

40 20. In a partition structure for prefabricated buildings, a partition support, a partition stud extending upwardly from said support, a stud connecting pad on said support beneath said stud and fixed thereto and to said support, partition 45 panels positioned by said stud and extending upright from said support, reenforcing means on opposite faces of said panels and having their lower ends laterally positioned by said support, coating anchoring means applied to the faces of said 50 panels and extending over said studs and spaced apart from said panels by said reenforcing means, and cementitious coatings on said anchoring means, said support having recesses and said reenforcing means extending beyond said panels into said recesses.

55 21. In a partition structure for prefabricated buildings, a partition support, a partition stud comprising oppositely disposed channels extending upwardly from said support, a pad on said support beneath said stud and fixed thereto and to said support, partition panels received in said channels and supported at their lower ends on said support, reenforcing rods on opposite faces of said panels having lower ends projecting beyond said panels in said support, coating anchoring means 60 applied to the faces of said panels extending over said studs and spaced apart from said panels by said reenforcing rods, and cementitious coatings on said anchoring means.

65 22. In a building, a supporting structure, an 70 upstanding channel member supported thereon, a stud member received in said channel member and having oppositely disposed channel portions, panels having adjacent edges received in said channel portions and end edges received in said 75

first mentioned channel member, and spaced means for connecting said channel member to the channel portions on said stud.

23. In a building, a floor supporting structure, a reinforced concrete floor thereon, partition studs including a partition stud having oppositely disposed channels and supported on said support-

ing structure and embedded in said floor, panels between said studs and received in said channels and having their lower edges embedded in said floor, and means embedded in said floor and fixed to said supporting structure and said stud for connecting the latter to said supporting structure. 5

AUSTIN T. LEVY.
